United States Patent Office

Des. 185,416
Patented June 9, 1959

185,416

SERVING SAUCEPAN

David Douglas, Manitowoc, Wis., assignor to East Wisconsin Trustee Company of Manitowoc, Manitowoc, Wis., a corporation of Wisconsin

Application March 17, 1958, Serial No. 50,055

Term of patent 14 years

(Cl. D44—1)

Fig. 1 is a view in front elevation of a serving saucepan embodying my new design;

Fig. 2 is a top plan view; and

Fig. 3 is a view in right side elevation thereof.

I claim:

The ornamental design for a serving saucepan, substantially as shown.
